UNITED STATES PATENT OFFICE.

ADELBERT HARRY RICHARDS, OF SALT LAKE CITY, UTAH, ASSIGNOR TO AMERICAN SMELTING AND REFINING COMPANY, A CORPORATION OF NEW YORK.

ORE COOLING, MOISTENING, AND FEEDING TABLE.

1,231,790.

Specification of Letters Patent. Patented July 3, 1917.

Application filed July 9, 1914. Serial No. 849,886

To all whom it may concern:

Be it known that I, ADELBERT H. RICHARDS, a citizen of the United States, and resident of Salt Lake City, in the county of Salt Lake and State of Utah, have invented certain new and useful Improvements in Ore Cooling, Moistening, and Feeding Tables, of which the following is a specification.

My invention relates to a cooling, moistening or feeding table for treating roasted ore as it passes from any roasting furnace, elevator or other mechanism having an intermittent discharge.

One of the objects of the invention is to provide a simple device for receiving the irregularly discharged ore from a furnace, roaster, driver, elevator or the like, for feeding ore or for thoroughly mixing and moistening hot ores and automatically delivering the cooled ore from the device in a continuous discharge after it has been subjected to this cooling and moistening treatment for a pre-determined period of time.

Another of the objects is to provide a device of the above indicated character, the parts of which may be conveniently assembled in position and which may be quickly demounted for cleaning and repairs.

The various other objects and advantages of the invention will be in part obvious and in part more fully set forth in the following description of my improved device, which consists in the new and novel steps and methods and also in the new and novel features of construction hereinafter set forth and claimed.

In the accompanying drawings:

Figure 1 is a vertical sectional view through a preferred embodiment of my invention shown in connection with the outlet portion of a furnace and with a receiving hopper; and

Fig. 2 is a plan view looking down on the table shown in Fig. 1.

In the drawings there is shown a furnace "1" which may be any suitable roasting furnace of that character which discharges the hot ore therefrom in an irregular or intermittent stream. Below the outlet "2" of this

furnace is positioned the mixing, cooling and discharging device "3" more particularly forming the subject matter of my invention. The device comprises suitable supports "4" preferably anchored to a foundation "5" and carrying an open bottom flat

cylindrical hood "6" which comprises a top plate "7" and a depending circular band "8" constituting the side of the hood. The hood is not an essential part of the construction, except when hot ores are to be cooled.

For convenience in construction, this hood is preferably formed of four castings, each comprising a sectoral part of the top plate with an adjacent portion of the side band integral therewith and these castings are suitably bolted together and to the supports "4."

The top plate "7" carries a hopper "9" arranged to direct the ore from the furnace outlet "2" on to a horizontal table "10" rotatably mounted within the hood and holds sufficient charge until next discharge is made, thereby giving a continuous discharge from any mechanism which has an intermittent discharge. To accommodate the hopper a portion of the plate is out-turned to form a thimble "11" upon the top of which rests an angled flange "12" in turn supporting the hopper. The table extends substantially to the band "8" to close the bottom of the hood and is reinforced adjacent its edge by a depending circular rim "13." The hood and table coact to form an inclosed casing having an outlet "14" at one side thereof leading to a conveyer belt "15" or to some other suitable conveyer, receptacle or continuously actuated grinding mill. The table is rotated by any suitable mechanism and for this purpose is shown resting on the radial ribs of a horizontally disposed spider "16" which has its center fixed to the upper end of a vertically disposed shaft "17." This shaft is suitably journaled in bearings "18" and "19," the latter of which is an end bearing supporting the shaft and the shaft is driven from a power shaft "20" through meshed beveled gears "21."

To protect the driving parts from the action of dust and loose particles of the ore, these bearings and gears are preferably inclosed within a gear box "22" which may form part of the support and in the disclosure illustrated provides a boxed structure for bracing the shaft journals in position.

Diametrically opposite portions of the band "8" are formed into open end seats "23" to support opposite ends of a rabble bar "21" in position just under the top plate. This bar preferably is in the form of an I-beam, extends through the hopper and car-

ries a plurality of rabble blades "25" removably mounted thereon and depending therefrom. These blades preferably have slotted heads "26" designed to be threaded 5 onto the lower flange of the I-beam to form a bank of blades and have vanes "27" projecting toward the table and disposed at an obtuse angle to the direction of movement of the ore on the rotating table and spaced 10 from each other to permit the movement of the ore therethrough. Several sets of blades can be used to meet certain conditions.

A spraying device "28" is fixed to the 15 plate "6" and is disposed above the table to moisten and cool or to moisten the ore as it is revolved and worked by the blades "25" toward the outlet. A water supply pipe "29" controlled by a valve "30" leads to the 20 spraying device, but this pipe may be used to convey cyanid or other chemicals to the agitated ores.

To assemble the device the several parts 25 of the hood are bolted to the support and the hopper inserted in the thimble, or in the event of the hood not being needed the hopper can be supported in any suitable manner. The rabble bar is then inserted through the open end of one of the seats and 30 through the hopper. The rabble blades, one after the other are inserted through the outlet from the casing and are threaded in order onto the lower flange of the bar, after which the bar is moved onto the other seat 35 and if necessary locked in position by any suitable means.

In operation, the ore is fed to a portion 40 of the table offset from its axis of rotation and the revolving table carries the ore into contact with the vanes of the rabble blades which vanes mix the ore and successively move the same outward toward the edge of the table. At the same time the ore is subjected to the cooling or moistening action 45 of the water spray, which action may be regulated by the amount of water fed to the device and by the speed of rotation of the table. The mixed ore, cooled and moistened, passes from the device into the storage hopper or conveyer belt to be subjected to its next treatment.

By means of a device of this character, the hot ore is quickly cooled, fine ore is quickly moistened and any ore is discharged 55 continuously, at little cost and accurate control of the operation is attained. The portion of the device receiving the ores may be conveniently demounted and the parts separated to clean or repair the same and all 60 mechanism is inclosed from the action of any loose ore or dust.

The positioning of the cooling device on one side of the table and the mixing blades on the opposite side causes first cooling of 65 the top layer of the ore for a certain period

of time while the table is rotating about one half of its circle of movement.

The gear box engages the shaft adjacent its connection with the spider, thereby bracing this shaft against bending strains and thus eliminates the necessity for any truck or support for the table. In this way, there is avoided any parts which might catch the loose particles of ore sifting down under the table to interfere with its rotation.

With this device it is immaterial whether the ore be fed to the same continuously or intermittently, the discharge onto the conveyer belt or mill will be continuous and this is of great advantage in certain continuously acting machines.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, what I claim as new and desire to protect by United States Letters Patent is:

1. In a device of the class described, the combination with a furnace having an irregular discharge of ore therefrom, of a horizontal table, means for rotating said table, a fixed hood inclosing said table to form an inclosed casing, said hood having rabble blades disposed in operative relation to said table to mix the ore carried thereby, a spraying device for directing cooling liquid to the ore on said table, a liquid conduit leading to said spraying device, said hood having an outlet for directing the ore from said furnace onto said table and the side of said casing having an outlet for the mixed and wet ore.

2. In a device of the class described, a substantially closed casing having a horizontally disposed rotatable bottom, said casing having an inlet at the top and an outlet at the side thereof substantially on a level with the bottom, a rabble blade fixed relative to the casing and disposed in operative position relative to said rotatable bottom to mix the ore thereon and to feed the ore uniformly through the outlet and means for cooling or moistening or mixing with chemicals the said ore as it is being fed toward the outlet.

3. In a device of the class described, a means for receiving and cooling, moistening or wetting an intermittently fed stream of ore, said means comprising a revolving table, an inclosing hood for said table, an outlet from said hood, a rabble blade supported from said hood and positioned to one side of the axis of rotation of the table and adapted to mix the ore on the table and uni-

- formly feed the same toward said outlet, and a spraying device supported from said hood on the side of said axis opposite the rabble blade.
- 5 4. In a device of the class described, the combination with a furnace having an irregular discharge of ore therefrom, of a horizontal table, means for rotating said table, a bank of rabble blades disposed in 10 operative position to said table to mix the ores carried thereby and extending diametrically of the table to one side of the axis of rotation, a spraying device for directing cooling liquid to the ore on the table and 15 disposed on the side of the axis of rotation opposite the bank of rabble blades, and means for directing the ore from the furnace to the table between the bank of rabbles and the spraying device.
- 20 5. In a device of the class described, the combination with a hopper adapted to contain a charge of ore, means for drawing said ore from the hopper in a uniform stream,
- 25 said means including a rotatably mounted table adapted to receive the ore, a bar disposed above the table, a plurality of rabble blades positioned on said bar, each of said blades having a vane disposed at an angle to the path of movement of the ore on the table and spaced from each other to permit 30 the passage of the ore therebetween, said blades being fastened to one side of the axis of rotation of the table acting on said ore to draw the same uniformly from said hopper toward the edge of the table to 35 spread the same evenly on said table, and a spraying device for subjecting the layer of ore on the table to a cooling treatment on the side of said axis opposite the rabble blades.

Signed at Salt Lake City, in the county 40 of Salt Lake, and State of Utah, this 22 day of June, A. D. 1914.

ADELBERT HARRY RICHARDS.
